UNITED STATES PATENT OFFICE.

PAUL DICKINSON, OF CHICAGO, ILLINOIS.

SMOKE-STACK.

SPECIFICATION forming part of Letters Patent No. 760,733, dated May 24, 1904.

Application filed November 20, 1903. Serial No. 181,967. (No model.)

To all whom it may concern:

Be it known that I, PAUL DICKINSON, a citizen of the United States, residing at Chicago, in the county of Cook and State of Illinois, have 5 invented a new and useful Improvement in Smoke-Stacks, of which the following is a specification.

My invention relates to improvements in adjustable smoke-stacks for locomotive round-houses; and my object is to provide certain improvements in the construction of such smoke-stacks and supporting means therefor whereby the stack may be readily raised, lowered, and moved back and forth to position it 15 with relation to the locomotive-stack.

In the drawings, Figure 1 is a vertical transverse sectional view taken on line 1 1 of Fig. 2, viewed in the direction of the arrow, and also on a line through the shafts F and f' at 20 the right of the section-line 1 1; Fig. 2, a broken section, on a reduced scale, taken on line 2 in Fig. 1 and viewed in the direction of the arrow; and Fig. 3, a broken sectional detail view taken on line 3 in Fig. 1.

A is the roof of a locomotive shed or round-house, provided with a longitudinally-extending opening a directly over the track on which the locomotive moves into its stall. Mounted upon the roof at opposite sides of said opening are parallel frames b b, supporting horizontally-extending rails c and guards d.

B is a frame of a vehicle or support of a length preferably nearly double that of the opening a and mounted on flanged end wheels 35 e and intermediate wheels f, all of which run upon the rails or track c. The frame B has a roof g, sides h, extending nearly to the surface of the roof A at the outer sides of the track-frame b, and ends i i. In the roof g is an opening j, fitted with a thimble or sleeve k, clamped by bolts k' between an upper flanged ring k² and a lower ring k³. The ring k² rests upon the frame of the roof g and supports a stationary stack-section l, surmounted 40 by a cowl l'. Mounted in the ring k² is a cross-shaft m. A stack-section n, having a thickened upper end portion n', provided with bearing-perforations, is pivotally supported at said perforations on the shaft m to swing 45 at its lower end a limited distance in the di-

rection longitudinally of the frame. Journaled in bearings on the frame B is a cross-shaft C, provided at opposite sides of the stack-section n with large chain-sheaves p, extending to the vertical plane of the center of 55 said section. Also upon the shaft C is a worm-wheel p'. Journaled in brackets on the frame B is a longitudinally-extending shaft D, running beneath the worm-wheel p' and having a worm D', meshing with the wheel p'. Also 60 upon the shaft D is a chain-sheave D², carrying a loose endless chain D³.

E is a lower stack-section fitting along its upper end loosely or telescoped in the section n and provided at its lower end with a hood 65 or inverted funnel E'. Chains E² are fastened at their lower ends to the lower end or funnel portion of the stack-section E at opposite sides thereof and are secured at their upper ends to the sheaves p.

The chain D³ hangs within convenient reach of an operator, and by drawing upon the said chain the shaft D is rotated to cause the worm D' to turn the worm-wheel p' and shaft C to turn the sheaves p, and thus raise or lower the 70 stack-section E.

The supporting-wheels f for the frame B are upon a cross-extending shaft f', which carries adjacent to the wheels f gear-wheels f². Above and parallel with the shaft f' is a cross-extending shaft F, journaled in the frame B and carrying pinions F' F', meshing with the gear-wheels f². On the shaft F is a chain-sheave F², carrying a hanging operating-chain F³, which also extends downward to be readily 80 reached by the operator. A pull upon the chain F³ causes it to rotate the sheave f² and shaft F, whereby the pinions F' rotate the gears f² and shaft f' to cause the wheels f to travel upon the track c, and thus move the 85 frame B and the smoke-stack along the opening a.

When a locomotive is moved into its stall, it may be stopped with its stack at any point between the ends of the opening a in the roof. 90 By drawing upon the chain F³ an operator may then move the frame B until the funnel end E' of the stack carried thereby registers with the locomotive-stack. By drawing upon the chain D³ the lower section E may be low- 95 100

ered to the locomotive-stack. Should the locomotive be moved while the section E covers the locomotive-stack, the said section E and the section n will swing upon the bearing m 5 to release engagement between the stacks.

While I prefer to construct my improvements throughout as shown and described, they may be variously modified in the matter of details without departing from the spirit 10 of my invention as defined by the claims.

What I claim as new, and desire to secure by Letters Patent, is—

1. In a locomotive-shed, the combination of a roof therefor, having an opening through it, 15 a smoke-stack support mounted to slide back and forth along said roof, and a smoke-stack on said support extending through said opening and adapted to be brought into operative relation with the stack of a locomotive.

2. In a locomotive-shed, the combination of a roof therefor having an opening through it, a smoke-stack support mounted to slide back and forth along said roof, and a smoke-stack carried by and depending below said support 25 and extending through said opening, and adapted to be brought into operative relation with the stack of a locomotive.

3. In a locomotive-shed, the combination of a roof therefor having an opening through it, 30 a smoke-stack support mounted to slide back and forth along said roof, and a smoke-stack carried by said support, extending through said opening and having a swinging section, depending below said support, and adapted to be brought into operative relation with the stack of a locomotive.

4. In a locomotive-shed, the combination of a roof therefor having an opening through it, 35 a smoke-stack support mounted to slide back

and forth along said roof, and a smoke-stack, 40 carried by said support, extending through said opening and having a telescoping section depending below said support and adapted to be brought into operative relation with the stack of a locomotive.

5. In a locomotive-shed, the combination of a roof therefor having an opening through it, 45 a smoke-stack support closing said opening and mounted to slide back and forth along said roof, and a smoke-stack carried by and extending through said support and adapted to be brought into operative relation with the stack of a locomotive.

6. In a locomotive-shed, the combination of a roof therefor having an opening through it, 50 parallel track-rails on the roof at opposite sides of said opening, a wheeled smoke-stack support mounted to move back and forth upon said track over said opening, and a smoke-stack on said support extending through said 55 opening and adapted to be brought into operative relation with the stack of a locomotive.

7. The combination of a locomotive-shed roof provided with an opening, of parallel 60 rails on said roof at opposite sides of said opening, an inclosed vehicle of greater length than said opening mounted to move on said 65 rails, and a smoke-stack mounted on said vehicle and extending downward through said opening, and adapted to be brought into operative 70 relation with the stack of a locomotive, the vehicle forming at all times a hood over said opening, substantially as and for the purpose set forth.

PAUL DICKINSON.
